UNITED STATES PATENT OFFICE.

ALPHEUS C. SHUTTLEWORTH, OF PHILADELPHIA, PENNSYLVANIA, ASSIGNOR
TO GEORGE DRAPER & SONS, OF HOPEDEALE, MASSACHUSETTS.

ELECTROMAGNETIC WARP STOP-MOTION FOR LOOMS.

SPECIFICATION forming part of Letters Patent No. 570,738, dated November 3, 1896.

Application filed April 30, 1894. Serial No. 509,446. (No model.)

To all whom it may concern:

Be it known that I, ALPHEUS C. SHUTTLEWORTH, a citizen of the United States, residing at Philadelphia, in the county of Philadelphia and State of Pennsylvania, have invented certain new and useful Improvements in Electromagnetic Warp Stop-Motions for Looms; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention has reference to a device for automatically operating the stopping mechanism of a loom electrically at the breaking or sagging of any of the warp-threads.

The invention consists in the use of a heddle-frame for the wire heddles, provided with either one or two permanent magnets, but where a single permanent magnet is used the heddle-frame is provided with a partially-insulated heddle-shaft. The aforesaid parts operate in conjunction with an electrical current by means of the heddle-wires coating with an electromagnet and such mechanical parts are arranged to displace the shipper-lever from the keeper-notch, and thereby stop the loom.

I have illustrated the invention by drawings herewith, in which—

Figure 1 is a side elevation, partly in section, of a form of loom, showing the principal parts of a loom, the electrical connections, and mechanical means employed in moving the shipper-lever. Fig. 2 is a face view of a heddle-frame constructed with a single permanent magnet and illustrating the positions occupied by the electrical and mechanical parts directly associated with it. This figure also shows the two positions of the wire heddles when the heddle-frame is at its highest position. Those wire heddles carrying broken or sagging threads are shown clinging to the permanent magnet. Fig. 3 is a similar view showing the lowest position assumed by the heddle-frame and provided with but a single permanent magnet, illustrating also the positions of the immediately-associated electrical and mechanical parts used in connection

with it, also showing the two positions of the heddle-wires when the heddle-frame is at the lowest position. Those wire heddles carrying broken or sagging threads are shown suspended upon the upper partially-insulated heddle-shaft. Fig. 4 is a vertical section at *x x* of a heddle-frame having a single permanent magnet. Fig. 5 is a face view of a heddle-frame constructed with two permanent magnets, this view showing also the electrical and mechanical parts operating with it. Fig. 6 is a vertical section at *y y* of Fig. 5. Fig. 7 is an enlarged cross-section of a permanent magnet. Fig. 8 is an enlarged cross-section of the partially-insulated heddle-shaft. Fig. 9 represents a single heddle-wire. The heddle-shafts are shown in cross-section in the eyes thereof.

Similar letters refer to like parts.

In the drawings, *A* represents the frame of a loom; *B*, the heddle-frames; *M*, the warp-beam; *S*, the lathe; *R*, the whip-roll; *H*, the treadles; *K*, the shipper-lever; *c*, the wire heddles, and *d* the warp-threads. All of the mechanical parts referred to are constructed and similarly used as in the ordinary form of loom.

In the construction of the heddle-frame *B*, carrying the wire heddles *c*, the top rail *b* is constructed of iron or steel, or a combination of both, and sufficiently magnetized to form a strong permanent magnet, and so is the bottom rail *b'* when constructed in the form of the modification, Fig. 5.

The two heddle-shafts *e e'*, upon which the wire heddles *c* are strung when using a single permanent magnet, as in Figs. 2 and 3, differ from each other, *e'*, located in the frame at the top, being made in the form of an inverted **V**. The entire surface of the upper bar *e'* is insulated, as *e''*, excepting the inverted-**V**-shaped portion. (See Fig. 8.) The bottom shaft *e* is of the form used in all heddle-frames, not being in any manner insulated from the wire heddles *c*, but they are directly connected by wires *l* with the source of electricity *L* for the purpose of allowing individual heddles in each set of heddles in their respective frames to act independent of other heddles in other frames in the completion of the electric circuit with the knock-off electromagnet.

The connection *l* may be made to any number of heddle-frames from a parent stem leading to the electric battery and thoroughly flexible in order to allow independent movement of any of the series of heddle-frames.

Secured firmly to the loom-frame *A* is a plate *g*, corresponding in width to the combined thickness of the number of heddle-frames used, and it is constructed with flanges 10 *g'* projecting at a right angle from its face at its extreme upper and lower ends, the upper flange engaging the spring-arm *n*, connected to the permanent magnet *b*, when the heddle-frame is at its highest position, and the lower 15 flange *g'* engaging the spring-arm *n'*, connected to the upper partially-insulated heddle-shaft *e'* at the lowest position assumed by the heddle-frame. These shafts and spring-arms are constructed and act similar in each 20 of the heddle-frames in use where a single permanent magnet forms the top rail of the heddle-frame.

An electromagnet *O* is located on the frame 25 of the loom in proximity to the shipper-lever *K* and the lathe *S*. The said lathe is provided with a slotted plate *s* for engaging the lever *r*, supported normally by the spring *v*. The lever *r* has pivoted to it a foot-piece *t* directly over the electromagnet *O*.

As before stated, an electric battery or other 30 source of electricity to operate the device is shown, located at *L* and connected by *l'* through the electromagnet to the flanged plate *g*, secured on the loom-frame, and the opposite side of the battery is connected by wires 35 *l''* to the heddle-frames.

At the highest position of a heddle-frame all of the heddle-wires *c* holding sound threads rest on the inverted-V-shaped edge 40 of the partly-insulated heddle-shaft *e'*, and all those heddle-wires *c'* carrying unsound or broken threads will adhere to the top magnet, being attracted by the magnetism, thereby completing the electric circuit 45 through the arms and upper flange of the plate *g*, through the electromagnet to the battery.

At the lowest position of the heddle-frame all wire heddles *c* holding sound threads 50 will be forced against the permanent magnet *b* and away from the partly-insulated heddle-shaft *e'* by the tension of the warp-threads *d*, and all those wire heddles marked *c'* carrying unsound or broken warp-threads will 55 instantly fall by reason of their own gravity on the shaft *e'*, thereby completing an electric circuit by a similar engagement of the spring-arm of the partially-insulated heddle-shaft *e'* engaging with the lower flange of the plate *g* 60 in a similar manner and means, as before explained.

When either of the circuits above described is formed, the electromagnet being in the circuit attracts the pivoted plate *t*, connected 65 to the spring-arm *r* in line to engage the projection *r'* by the slotted plate *s* and force the nose of the spring-arm *r* against the pro-

jection *k* on the shipper-lever *K*, and thereby dislodge the latter from the keeper-notch, so that the loom will be able to make but a single pick when the circuit is completed.

The replacing of the shipper-lever in its proper position to run the loom will arrange the knocking-off spring-lever *r* instantly in place, ready to be again operated upon. The 75 spring-lever *r*, when struck by the lathe, slides forward in the keeper *v'*.

For weaving with heavy warp-threads and to insure greater efficiency in the completing of the electric circuits I dispense with the 80 partly-insulated heddle-shaft *e'*, using uninsulated and similarly-shaped shafts for the heddle-wires, in which case the bottom rail *b'* of each of the heddle-frames would also be constructed with a permanent magnet, the same 85 as the top rail *b*. (See Figs. 5 and 6.) Such construction would simply require the lengthening of the plates *g* and supplying the lower permanent magnet *b'* with a spring-arm *n'*, the same as the top magnet, and the circuits 90 produced at the highest position of the heddle-frame would be through the wire heddles *c*, plate *g*, and electromagnet *O*, by means of the wires, to the battery at one end, and the wire heddles, lower heddle-shaft *e*, and wires 95 *l'* to the battery *L* upon the opposite end.

I claim—

1. In an electric warp stop-motion for looms, the combination with a heddle-frame, of a permanent magnet carried thereby, a series 100 of heddles normally held out of contact with said permanent magnet by the tension of the warp-threads, a source of electrical energy with which said permanent magnet and heddles are in circuit, an electromagnet in circuit 105 with said permanent magnet and heddles, and a shipper-lever controlled by said electromagnet so that when tension on any one of the series of heddles is relaxed so as to allow contact with said permanent magnet the circuit is completed and the loom 110 stopped.

2. In an electric warp stop-motion for looms, the combination with a heddle-frame, of a permanent magnet carried thereby, a series 115 of heddles normally held out of contact with said permanent magnet by the tension of the warp-threads, a source of electrical energy with which said permanent magnet and heddles are in circuit, an electromagnet in circuit 120 with said permanent magnet and heddles, a spring knock-off lever controlled by said electromagnet, a shipper-lever actuated by said knock-off lever, so that when tension on any one of the series of heddles is relaxed so 125 as to allow contact with said permanent magnet the circuit is completed and the loom stopped.

3. In an electric warp stop-motion for looms, the combination with a heddle-frame, of a permanent magnet carried thereby, a series 130 of heddles normally held out of contact with said permanent magnet by the tension of the warp-threads, a source of electrical energy

with which said permanent magnet and heddles are in circuit, an electromagnet in circuit with said permanent magnet and heddles, a spring knock-off lever controlled by 5 said electromagnet, a shipper-lever actuated by said knock-off lever, connection between said knock-off lever and the lathe by means of which the said knock-off lever is moved at the forward movement of the lathe so as to 10 throw the shipper-lever and stop the loom when tension on any one of the heddles is relaxed so as to allow contact with the permanent magnet and completion of the circuit.

4. In an electric warp stop-motion for looms, 15 the combination with a heddle-frame, of a permanent magnet carried thereby, a series of heddles normally held out of contact with said permanent magnet by the tension of the warp-threads, a source of electrical energy 20 with which said permanent magnet and heddles are in circuit, a shipper-lever, a knock-off lever to actuate the shipper-lever mounted on the loom-frame so as to be normally out of the path of movement of the lathe, and an 25 electromagnet in circuit with said permanent magnet and heddles to attract said knock-off lever and throw it into the path of said lathe when the circuit is completed by the slackening of a warp-thread and the resultant 30 movement of a heddle into contact with the permanent magnet.

5. In an electric warp stop-motion for looms, 35 the combination with a heddle-frame, of a permanent magnet carried thereby, a heddle-shaft insulated on its bottom and two sides, a series of heddles normally held out of contact with said magnet by the tension of the warp-threads, a source of electrical energy with which said permanent magnet and heddles 40 are in circuit, a conductor-plate on the loom-frame with which said heddle-frame contacts at each shed, a spring knock-off lever to actuate the shipper-lever mounted in a

slide on the loom-frame normally out of the path of movement of the lathe, an electromagnet in circuit with the permanent magnet and the said heddles in close proximity to said spring knock-off lever to attract the same and throw it into the path of movement of the lathe when said electromagnet is energized by the completion of the circuit through the slackening of the tension of any one of the warp-threads and the resultant movement of a heddle, and a projection on the lathe to engage said knock-off lever and force it forward to actuate the shipper-lever and stop the loom.

6. In an electric warp stop-motion for looms, the combination with a heddle-frame, of one or more permanent magnets carried thereby, 60 a series of heddles normally held out of contact with said permanent magnets by the tension of the warp-threads, a source of electrical energy with which said magnets and heddles are in circuit, an electromagnet in circuit 65 with said heddles and said permanent magnets, a spring knock-off lever controlled by said electromagnet, a projection on the lathe which engages the said knock-off lever when the latter is thrown into the path of movement of the lathe by the action of the electromagnet, a shipper-lever which is actuated by said knock-off lever to stop the loom, a conductor-plate on the loom-frame, spring-arms 70 on the heddle-frame which contact with said conductor-plate at the end of each shed and complete the circuit when any one of the heddles is thrown from its normal position by the slackening of the tension of a warp-thread.

In testimony whereof I affix my signature 80 in presence of two witnesses.

ALPHEUS C. SHUTTLEWORTH.
